UNITED STATES PATENT OFFICE.

FRANK. F. DRINKHOUSE, OF EASTON, PENNSYLVANIA.

FEED-CUTTER.

SPECIFICATION forming part of Letters Patent No. 440,021, dated November 4, 1890.

Application filed April 23, 1890. Serial No. 349,113. (No model.)

To all whom it may concern:

Be it known that I, FRANK. F. DRINKHOUSE, a citizen of the United States of America, residing at Easton, in the county of Northampton and State of Pennsylvania, have invented 5 certain new and useful Improvements in Feed-Cutters, of which the following is a specification, reference being had therein to the accompanying drawings.

10 My invention pertains to an improvement in feed-cutters; and it consists in the novel construction, combination, and arrangement of the parts, substantially as hereinafter more fully described, and shown in the accompanying drawings, in which—

Figure 1 is a longitudinal section of my invention. Fig. 2 is a plan view. Fig. 3 is a front elevation thereof, parts being broken away; and Fig. 4 is a plan view of my improved 15 feed-cutter.

The object of my improvement in feed-cutters is to compact the feed under the cutting-knife in order not only to facilitate the cutting operation, but to improve the quality of 20 the cut feed as to length and compactness.

In the embodiment of my invention the feed-box A is suitably supported on legs B B and C, the former mortised in foot-piece d and connected to the leg C by the mortised longitudinal bar e, the walls of the feed-box being 25 slightly converged from rear to front.

The front of the feed-cutter has resting on its longitudinal sides or walls a metallic bridge f, and is there secured, screwed down 30 by means of its shoulders g.

E is the compressor, consisting of a plate hinged or pivoted near its rear end or edge upon a cross-rod E' held in or to the bridge f at its front end. The rear or upper edge of 35 the plate is provided with an upturned lip or stop D, adapted to engage the rear edge or end of the bridge f, and from the upper side of the said plate projects a hinged handle or bar h, extending a short distance out through 40 a longitudinal slot i in the center of the bridge. The handle or bar h provides for holding the 45 compressor down upon the feed, in cutting it

long as the latter is passed to the cutter, and to permit the elevation of the outer end of the compressor, when required. The handle or 50 bar h has a side edge at h', adapted to engage a ratchet i', formed of one side wall of the slot i, whereby the compressor may be vertically adjusted and retained at its point of adjustment, as circumstances may require. Inclined bar h is encircled by coiled spring h' 55 and rigidly secured by ordinary means to compressor E. The ends of the coiled spring are secured one to the compressor E and the other end to the bridge f, and spring-bar h 60 serves as an adjunct in forcing down the compressor, since lip D of the compressor, as the compressor's outer end is elevated by the feed in its passage, as aforesaid, is pressed and curved downwardly, thus forcing the spring-bar h outwardly, and greatly increasing the 65 elastic power of the compressor on the feed near the cutting-knife G, the point where it is most necessary that the feed should be compacted.

The frame of the cutter has secured to the lateral front thereof the smooth metallic guide-frame H, having pivoted, as shown, thereto the knife K, provided with a suitable handle for its manipulation.

Having thus fully described my invention, what I claim, and desire to secure by Letters Patent, is—

In a feed-cutter, the combination, with the frame, the pivoted knife, and the floor and side walls of the feed-throat, of the bridge having the longitudinal ratchet-toothed slot, the compressor hinged at the front end of the bridge and having the upturned lip or stop abutting or engaging said front end, the hinged adjusting-bar h, and the spring h', substantially as and for the purpose set forth.

In testimony whereof I affix my signature in presence of two witnesses.

FRANK. F. DRINKHOUSE.
